ELECTRONIC DEVICE

William Ross Aiken, Los Altos, Calif., assignor, by mesne assignments, to Kaiser Industries Corporation, a corporation of Nevada

Application August 1, 1955, Serial No. 525,649

10 Claims. (Cl. 315—27)

The present invention is directed to a new and novel cathode ray tube, and particularly to a novel cathode ray tube including a novel electronic scanning arrangement.

The tube of the present invention is of the revolutionary tube type known in the art as the Aiken-type flat cathode ray tube which has been disclosed in Patent 2,795,731, which issued June 11, 1957, to W. R. Aiken.

The Aiken tube in its basic concepts, is comprised of a configuration which approximates that of a picture adapted for wall mounting, and is comparable in size and shape to a metropolitan telephone directory.

As illustrated in Figure 1, one embodiment of the Aiken tube (the so-called double bend tube disclosed more fully in the above identified applications) employs an electrostatic beam bending principle to bend an electron beam which is delivered along a marginal edge of the tube from such path through an angle of approximately 90°, and thereafter a second set of electrostatic beam bending devices apply further forces to bend the beam approximately perpendicular to the second path and into registration with a target. Inasmuch as the electron beam has a considerable velocity as it leaves the gun along its first path, the initial bending forces provided by the electrostatic member may be less than is required to bend the beam through the full 90°, and in such event the marginal edges of the display will be canted slightly relative to the vertical. In Patent No. 2,864,970 issued Dec. 16, 1958, to W. R. Aiken, there is described a mechanical method for adjusting the marginal edges of the raster. The present invention relates to novel magnetic means and method for effecting adjustment of the raster marginal edges and particularly for simplifying the method of straightening the edges of the television picture produced on an Aiken-type flat cathode ray tube.

Figure 1 is a diagrammatic perspective view showing the basic components of an Aiken tube where the electron gun is disposed parallel and adjacent to the vertical marginal side of the tube.

Figure 2 is a front view of an Aiken tube showing the disposition of the magnetic picture straightener.

Figure 3 is a plan view of an Aiken tube showing the relative disposition of one embodiment of the magnetic picture straightener.

Figure 4 is a front view of an Aiken tube showing another embodiment of the magnetic picture straightener.

A general description of the configuration and operation of the Aiken tube in its most basic arrangement is set forth for the purpose of simplifying the explanation of the improvements to which this invention relates. The tube, as schematically shown in Figure 1, comprises a housing, not shown, within which are located an electron gun 12, a primary section 14, including a set of horizontal plates 16, a transition section (not shown in Figure 1 but located in the space indicated at 17), a high voltage section 18, including a set of vertical plates 20, and a target 22.

In operation, selected areas on the phosphor screen are electronically excited by the electron beam. In the illustration, the electron gun 12 is located at the lower left-hand corner of the viewing screen and is adapted to deliver a beam along the lower horizontal edge of the

2

phosphor screen in a field-free region adjacent the horizontal deflection plates 16. Control means effect the application of voltages selectively to each of the horizontal deflection plates to effect bending of the beam vertically at corresponding points along the edge of the tube and upward through the transition section 17 and into the second field-free region between the transparent flat deflection plates 20 and the electrically charged screen 22.

10 Deflection of the beam onto the screen at the vertical level is achieved by effecting the application of voltages of appropriate values to corresponding ones of the vertical deflection plates. Thus the position of the beam on the target may be controlled by the application of voltages to the corresponding ones of the horizontal and vertical deflection plates.

15 In the utilization of the equipment in the presentation of a raster, the horizontal deflection plates are energized in a selective manner by a first set of voltages, and the vertical deflection plates are energized correspondingly by a second set of voltages synchronized with that applied to the horizontal deflection plates.

20 In one embodiment, the horizontal and vertical plates are kept at a high voltage except for those opposite the position in which the beam is to be bent. In another embodiment, the horizontal and vertical plates are negative, and are synchronically energized at the point at which the beam deflection is desired. It is obvious to those skilled in the art that one set of plates may be initially negative and the other set of plates may be initially positive, in which event the beam bending signals will be varied accordingly.

25 Briefly, the manner of operation of the elements in the use of the tube with a television receiver unit adapted to respond to commercial television broadcasts is as follows.

30 The horizontal sync pulses obtained from the video amplifier of a conventional television receiver chassis are applied through appropriate circuitry to the horizontal deflection plates to accomplish a line sweep in the conventional manner at the rate of approximately 260 lines per vertical sweep (assuming an interlaced trace arrangement) and the vertical sync pulses obtained from the video amplifier section of the conventional television receiver chassis are applied to the vertical deflection plates to accomplish a vertical sweep each $\frac{1}{30}$ of a second (30 pictures per second). The video amplifier output is applied to the cathode (or grid) of the electron gun whereby variations of the gun intensity resulting from the signals received at the television receiver appear as variations in intensity of the beam on the target and, accordingly, effects the presentation of the picture transmitted by the television station.

35 The electron beam has a considerable velocity when it leaves the electron gun and its deflection by the horizontal plates 16 which form the means for making the first bend of the beam may not be sufficient to bend the electron beam the full 90°. This effect is attributable to the speed of the electron beam and can be graphically represented by a vector of the energy of the electron beam coupled with the deflection energy of the horizontal plate 16. In such event, the vertical marginal edges of the resultant television picture are canted.

40 The inventor has found that the beam can be adjusted to a path which is truly vertical to the horizontal with a minimum of equipment and electronic circuitry. Specifically the inventor has employed a magnetic field surrounding the transition section 17 of the tube just above the primary section 14 described generally in Figure 1, and has found that by proper application of a magnetic field, the picture can be straightened to produce a truly rectangular display.

More specifically with particular reference to Figure 2, there is shown an electromagnetic member having elongate legs or pole pieces 23 adapted to extend the entire length of an Aiken flat tube. The magnet is energized by an electrical winding 26 adapted to be wound about the base 27 of the magnet and in turn connected to a power supply. In one successful embodiment of the invention, it was found that very satisfactory results were obtained by employing a magnetic field strength of from 100 to 300 gauss.

In practice it has been found that there is a tendency for the electron beam to bend upwardly toward section 18 at its end farthest from the electron gun. For this reason, it is sometimes desirable to provide a smaller magnetic force at that end than at the end nearest the gun. In the embodiment shown in Figure 3, the difference in magnetic field intensity was successfully obtained by forming the magnet in such a fashion that the legs 25 of the magnet are spaced closer together in the region close to the electron gun than the spacing between the legs at the opposite end.

Figure 4 shows another embodiment of the magnetic picture straightener wherein the pole pieces 28 are made larger at the end nearest the electron gun in order to increase the magnetic field. This is an alternative to the method employed in Figure 3 wherein the ends of the pole pieces were placed closer together at the end nearest the electron gun.

In practice, the magnet may be tilted with respect to the horizontal deflection elements in order to achieve the proper adjustment of the resultant display. In some instances, the mechanical tilting of the electromagnet will amply serve to correct for any distortion or non-rectangularity of the television picture without requiring adjustment of the spacing of the legs of the magnet along its length in the manner of the showing in Figure 3, or the altering of the configuration of the magnetic legs as in the embodiment shown in Figure 4.

In operation, the magnet is energized by the power supply and thereby establishes a magnetic field which aids the horizontal deflection elements in the bending of the beam through the full 90° angle. The electron beam will then travel along a path perpendicular to its initial path of travel as it emerges from the electron gun.

It will be obvious to those skilled in the art that a permanent magnet having the proper magnetic field intensity may be successfully employed without avoiding the scope of the invention or necessitating additional research to practice the teachings of the invention.

What is claimed is:

1. In an electron discharge device, an electron beam source for delivering a beam along a given path, a first deflection means disposed along a segment of said beam path for applying deflection forces to said beam to selectively bend same from said path at successive different intervals along said segment, and auxiliary deflection means disposed coextensive with said path segment and operable to apply deflection forces to said segment of the beam which are of different values at said successive different intervals, said auxiliary deflection means being operable to provide a field of a first relatively large value at the intervals of said segment which lies closer to said source and forces of decreasing value at the intervals of said segment which are successively removed from said source, whereby the beam is bent from said segment through the same angle at said successive intervals of said segment.

2. An electron discharge device, an electron beam source for delivering a beam along an initial path, a first deflection means disposed adjacent one side of a segment of said beam path for applying deflection forces to said beam to effect selective deflection of the beam from successive intervals of said path segment, and auxiliary deflection means comprising at least a pair of spaced magnetic members which are disposed in facing spaced relation on a second and third side of said segment of

5 said beam path to establish a field therebetween which extends across the path of travel of the beam to further aid said first deflection means in the deflection of the beam from said path, said pair of magnetic members and said first deflection means extending substantially coextensively along said respective sides of said path segment.

3. A cathode ray tube comprising a target, an electron beam source means for delivering a beam of electrons 10 along a marginal edge of said target, a first means for applying forces into the beam for deflecting the beam into a zone adjacent said target, a second means for applying magnetic forces to increase the angle of deflection effected by said first means, and a third means for applying forces 15 to the beam causing the beam to be deflected from said zone toward and into registration with said target.

4. A cathode ray tube comprising a target, an electron beam source means for delivering a beam of electrons along a marginal edge of said target, means operable to selectively deflect the beam to a zone adjacent a surface of said target, magnetic means disposed relative to said last mentioned means to effect supplemental deflection of the beam, and means operable to selectively deflect the beam from said zone toward and into impingement with said target.

5. A cathode ray tube in accordance with claim 4 in which said magnetic means is disposed relative to the means operable to selectively deflect the beam to a zone adjacent a surface of said target in a plane not parallel to said last-mentioned means.

6. A cathode ray tube comprising a target, an electron beam source means for delivering a beam of electrons along a path in spaced offset and substantially parallel relation with respect to a marginal edge of said target, means for applying electrostatic forces to the beam from said path for deflecting the beam to a zone adjacent said target, magnetic means operative to increase the angle of deflection of the beam, and means for applying forces to the beam causing the beam to be deflected from said zone toward and into registration with said target.

7. A cathode ray tube in accordance with claim 6 wherein said magnetic means comprises a magnet having its pole pieces formed so as to be closer together at the end nearest said electron beam source than at the other end.

8. A cathode ray tube in accordance with claim 6 wherein said magnetic means comprises a magnet having its pole pieces formed larger at the end nearest said electron beam source than at the other end.

9. A cathode ray tube comprising a target, an electron beam source means for delivering a beam of electrons along a marginal edge of said target, a deflection set for applying deflecting forces to the beam to cause the beam to travel to a zone adjacent a surface of said target, a 55 U-shaped magnet disposed with its legs disposed on opposite sides of said deflection set to increase the angle of deflection of the beam, and means operable to selectively deflect the beam from said zone and into impingement with said target.

10. A cathode ray tube in accordance with claim 9 wherein said U-shaped magnet is of diminishing width along its length to thereby establish a stronger magnetic field at one of its extremities than at the other.
